LAND LEVELER

James R. Marvin, Knights Landing, Calif.

Application December 5, 1936, Serial No. 114,386

3 Claims. (Cl. 37—153)

This invention relates to land levelers and particularly to a finish leveler of the "float" type (as distinguished from the "drag" type) adapted for use after the initial or rough leveling has been accomplished with other equipment.

The principal object of my invention is to provide a land leveler of the above type which is wheel-supported so as to reduce the frictional resistance of the leveler to movement along the ground and which, due to its relatively great length, is extremely efficient in working the ground to an accurately level surface.

A further object is to so construct and mount the leveler that no furrows or ridges will be made in the ground by the bowl of the leveler when making turns, and without the necessity of the operator raising the bowl clear of the ground when the leveler is thus turning.

A further object is to provide a leveler of this character arranged so that its length may be altered as the operating conditions may determine to be best.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of the leveler in its relatively short form, the bowl being in its lowered operating position.

Fig. 2 is a sectional elevation of the leveler with the bowl raised.

Fig. 3 is a side elevation of the leveler as increased in length by the additions of the extensions.

Fig. 4 is a fragmentary plan partly in section showing the connecting means between the main and extension frames of the leveler and a wheel unit.

Fig. 5 is a fragmentary transverse section of the leveler showing the bowl control mechanism.

Referring now more particularly to the characters of reference on the drawings, the main permanent frame of the leveler includes horizontal side beams 1 spaced a suitable distance apart, of hollow form and preferably about thirty feet in length. These beams are connected at intervals by cross-beams 2 and are braced against longitudinal deflection or sag in a vertical frame

by top and bottom truss frames 3, which include central posts 4.

The main frame is supported at each end by a pair of castor wheels 5 mounted in connection with a cross-beam 6 at such points thereon that the wheels are substantially in line with the beams 1. The cross-beam 6 is provided with rigid horizontal tongues 7 positioned to project into the adjacent open end of the beams 1 so that the cross-beam and side beams are rigidly connected together. A rigid rectangular frame structure is thus provided, at the four corners of which the wheels are disposed. The tongues are removably secured in place by suitable means, such as pins 8, projecting through said beams 1 and the tongues. The front cross-beam 6 has depending arms 10 to which hauling chains 11 or the like may be connected, as shown in Fig. 2.

Supported from the frame and disposed between side beams 1 is the bowl or ground engaging member of the leveler, which comprises a substantially semi-circular bowl portion 12, provided with forwardly projecting side wings 13. These wings at their forward end and top are pivotally connected to brackets 14 secured on and depending from the beams 1 and positioned so that the cutting edge E of the bowl is midway of the length of the wheel base when the wheels are in their normal trailing position.

The cutting edge E of the bowl is adjustable to any desired working level, or the bowl as a whole raised well clear of the ground for transportation purposes by the following means.

Journalized in bearing boxes 15 mounted for vertical adjustment in hangers 16 supported from the side beams 1 above the bowl at its rear end is a transverse shaft 17. Radial arms 18 are secured on this shaft and are connected to the back of the bowl adjacent its sides and about midway of its height by links 19. In operation, when the arms and links are in depending dead-center alignment, the cutting edge of the bowl is in a working position, and at a level determined by the level of the shaft, which may be adjusted to suit by adjusting the journal boxes in the hangers.

Rotation of the shaft is manually controlled and said shaft normally locked against rotation by a worm wheel 20 on the shaft engaged by a worm 21. This worm is rotated by a hand wheel 22, which is supported for vertical adjustment to match with that of the shaft, by suitable means such as cooperating relatively slidably bracket plates 23, one of which is mounted on the adjacent cross-beam 2 of the main frame, as shown in Fig. 5.

From the above description, it will be seen that owing to the relatively great length of the supporting frame and of the wheel base, which determines the points of support of said frame from the ground, the bowl levels off any inequalities in the ground over which the machine travels without digging down in the holes or depressions, just as a long plane acts on a piece of wood. The round form of the bowl causes the dirt, as gathered into said bowl with the forward movement of the leveler, to be churned and rolled about, so that any clods, if present, are pulverized before being left behind as the bowl passed over any low places in the ground. The castor mounting of the wheels and the fact that the bowl is positioned centrally of the length of the wheel base insures that the bowl will not at any time dig into the ground and make furrows or ridges when turning.

If a leveler of greater length than above described is desired, I provide for increasing such length by means of extension frames adapted to be mounted on and project from both ends of the main frame unit, and in the outer ends of which the wheel units will then be supported, as shown in Fig. 3. Each extension frame includes hollow side beams 24 spaced the same as the beams 1 and about one-half as long, though of course such length may be varied to suit. The beams 24 have tongues 25 projecting from one end to fit into the beams 1 at either end in place of the tongues 7. At their opposite end, the beams 24 are open to removably receive the tongues 7 of the wheel unit. (See Fig. 4.) The same pins 8 used to secure the tongues 7 to the beams 1 also serve to secure the tongues 25 to said beams, or the tongues 7 to the beams 24. The length of the leveler may thus be increased by 100% or more, if desired, and the degree of fineness of the leveling action is correspondingly increased, as will be obvious.

In order to brace this long frame structure as a whole against deflection, vertical posts 26 are mounted on and project both above and below the beams 24 from adjacent the ends thereof nearest the main frame. (See Fig. 3.) Cables 27 or the like extend from anchor points on the beams 24 at their outer ends over the posts 26 in engaging relation therewith, to detachable connection with the post 4 at the outer ends thereof. Turnbuckles 28 in the cables enable the desired degree of tension to be obtained after the cables have thus been connected up.

From the foregoing description it will be readily

seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A land leveler comprising a main frame, a ground working member mounted on said frame, wheels supporting said frame at one end, an extension frame adapted to project from an inception at the opposite end of the main frame, means to detachably connect the adjacent ends of the frames together, a wheel unit, and means to removably connect said unit to the outer end of the extension frame or to said opposite end of the main frame when said extension frame is removed.

2. A land leveler comprising a main frame, a ground working member mounted on said frame, wheels supporting said frame at one end, said main frame including members forming longitudinally extending sockets open at the opposite end of the main frame, an extension frame, tongues at one end of said extension frame adapted to fit said sockets, the other end of the extension frame being formed with sockets spaced apart the same distance as the main frame sockets, a cross-beam, wheels supported from said cross-beam, and tongues projecting from said cross-beam to removably project into the sockets either of the extension frame or the main frame.

3. A land leveler comprising a main frame which includes relatively long side beams, wheels supporting said frame at one end, a ground working member mounted on the frame, a vertical brace structure applied to the side beams to prevent deflection thereof in a vertical plane, an extension frame adapted to project from and be connected to the opposite end of the main frame and including side beams alined with the side beams of the main frame, wheels supporting the extension frame at its outer end, and a vertical brace structure mounted on the extension frame beams and detachably connected to the brace structure of the main frame intermediate the ends thereof, whereby to maintain the entire frame unit against vertical deflection.

JAMES R. MARVIN.
